UNITED STATES PATENT OFFICE.

CHARLES F. DINGMAN, OF PALMER, MASSACHUSETTS, ASSIGNOR OF ONE-HALF TO
FLYNT BUILDING AND CONSTRUCTION COMPANY, OF PALMER, MASSACHU-
SETTS, A CORPORATION OF MASSACHUSETTS.

BUILDING CONSTRUCTION.

1,197,716.

Specification of Letters Patent. Patented Sept. 12, 1916.

Application filed January 24, 1916. Serial No. 73,979.

To all whom it may concern:

Be it known that I, CHARLES F. DINGMAN, a citizen of the United States, residing at Palmer, in the county of Hampden and State of Massachusetts, have invented certain new and useful Improvements in Building Construction, of which the following is a specification, reference being had to the accompanying drawings.

10 This invention relates to building structures and more particularly to an improved roof construction for dye houses, foundries, and the like.

It is commonly known that, in the dyeing of certain kinds of textile materials, the vapors which arise from the dye vats, form a temporary deposit upon the wood or steel roof structure and the condensation from this vapor with the dissolved or combined chemicals falls down into the room and onto the fabrics and spots the latter. Several remedies for such objectionable conditions have been suggested, one of which consists in the provision on the central ridge of the roof of a monitor or turret extending the entire length of the roof structure and having a plurality of windows in the opposite sides thereof which may be opened to permit the escape of the vapors and ventilate

30 the interior of the structure. In the construction of such a roof, steel beams and trusses and wooden roof sections or concrete roof slabs are employed, the latter being the most generally adopted material, as it

35 has been found that the drippings from concrete are practically pure water and, therefore, do not spot the fabrics. This has led to the use of reinforced concrete construction which, however, has the serious 40 disadvantage that the large concrete girders or beams greatly interfere with the light, present a great amount of condensing surface, and interfere with the rapid escape of the steam and vapors.

45 It has, therefore, been my object and purpose to devise an improved roof structure especially designed for dye houses, preferably using reinforced concrete in the construction thereof so as to render the roof 50 entirely fireproof but, at the same time, presenting a minimum surface for condensation of the vapors, and also realizing considerable economy in the use of concrete and the steel reinforcement therefor.

It has further been my object to provide 55 means in the roof structure to facilitate the escape of the vapors but without offering any material interference to the free entrance of light to the interior of the structure.

With the foregoing in mind, the invention consists essentially in the provision of transversely disposed cantaliver girders suitably mounted and supported upon the vertical walls or columns of the building and 60 upon which the roof structure is arranged and secured. This roof structure includes a shallow ridge from each of the longitudinal edges of which a series of ventilating 65 cowls or windows project outwardly and upwardly, the same being preferably of saw-tooth form, and means depending from the longitudinal edges of the ridge to aid in directing the rising vapors through the openings in the vertical walls of the saw-tooth 70 windows.

It is an additional general object of the invention to provide a roof construction for buildings which will not add materially to the cost of erection over that incurred in the 80 usual building of this type, and to provide means which will efficiently accomplish the above stated objects.

With the above and other objects in view, my invention consists in the novel features 85 of construction, combination and arrangement of parts to be hereinafter more fully described, claimed and illustrated in the accompanying drawing, in which,

Figure 1 is a partial transverse section 90 through a roof structure designed in accordance with the preferred embodiment of my invention; Fig. 2 is a vertical sectional view taken on the line 2—2 of Fig. 1; Fig. 3 is a similar view showing a slightly modified construction; and Fig. 4 is a similar view showing another alternative form.

Referring in detail to the drawing, 5 designates one of the side walls or columns of the building structure which will be suitably reinforced against vertical tensile strains and possible buckling, and 6 indicates a central isolated column or support. A series of roof supporting beams or girders 7 are provided. These beams are preferably of cantaliver type, and the outer end of one beam is suitably mounted and supported upon the wall or column 5, and the

corresponding end of the other beam similarly supported by the central column 6. These beams are of reinforced concrete, the steel reinforcements thereof constituting 5 what is in effect, a continuation of the steel reinforcing structures of the columns 5 and 6. The beams 7 incline upwardly toward each other and are suitably tied or joined together at their smaller ends, which constitutes one of the ridge points or apexes 10 of the roof. It will be understood that this mounting and arrangement of the girders 7 is duplicated on each side of the central column or support 6. I do not, of course, limit 15 myself to any particular arrangement of the reinforcing elements for the beams 7 or the supporting columns, as various metal reinforcement constructions might be employed for this purpose.

20 Upon the joined or connected ends of the beams 7, the roof ridge 8 is mounted and supported. This ridge may be constructed of metal in the form of a longitudinally extending beam, or a skeletonized metal beam may be employed as a reinforcement 25 for a concrete ridge. This beam is provided at its opposite longitudinal edges with the downwardly projecting ribs or flanges 8'. From the opposite longitudinal edges of the 30 ridge structure 8, the top walls 9 of the cowls or windows extend upwardly to the vertically disposed walls 10 which are provided with ventilating openings 11 adapted to be closed when desired, by means of the 35 swinging windows 12 mounted therein. These cowls or windows are arranged in saw-tooth formation longitudinally of the roof, and may be separate and distinct from each other, or a single top wall 9 may 40 connect each series of windows. The concrete structure of the beams or girders 7 has integral, upwardly extending webs 13 which sustain and reinforce the top walls 9 and the vertical walls 10 of the saw-tooth 45 ventilating windows or outlets. As shown in Fig. 2, these webs may be cut away, as indicated at 14, so as to afford communication between the several windows in each series, or the web may be continuous, and between 50 the top wall and the beam or girder 7 so as to separate the ventilating openings from each other. As indicated in Fig. 4 of the drawings, each of the saw-tooth cowls or 55 windows may be separate and distinct and provided with spaced vertical walls connected by a top wall.

At the center of the building, the downwardly converging roof walls 15 are mounted and supported on the beams 7, and at 60 the juncture of these walls a depending longitudinally extending rib or flange 16 is provided, while upon the outer edge of each wall 15, the vertical wall 10 of an inner series of ventilating cowls or windows 9 65 are supported. The rib 16 directs the ris-

ing vapors in opposite directions to the two central series of ventilating window openings. The ribs 8' also serve as baffles to prevent the inward flow of the smoke and gases after striking the walls 9 and thus 70 act to direct the same through the window openings 11. In dye houses, the vats would be located in parallel rows beneath the windows 9 so that practically all of the gases will arise at opposite sides of the roof ridge 75 8. Contrary air currents entering through the openings 11 would tend to deflect some of the gases inwardly, and such deflection of the gases is prevented by the ribs or baffles 8'. These ribs also reinforce or 80 strengthen the roof structure at the juncture of the walls 8 and 9. It will be understood that the wall 15 is also preferably of reinforced concrete or other similar material. The slope of the ridge walls 8 and of the 85 walls 9 of the saw-tooth ventilating windows or cowls is such as to facilitate the rapid escape of the vapors striking said wall through the window openings.

From the foregoing description, it will 90 be seen that the improved roof construction affords a minimum surface for condensation of the vapors, nor does it in any way interfere to any material extent with the free entrance of light to the interior of the 95 structure. By means of the proposed new construction, considerable economy may also be effected in the use of concrete and its accompanying reinforcement. While it has been demonstrated in practice that concrete 100 is the best material to use in the construction of dye houses for the reasons hereinbefore referred to, it is manifest that the principle employed may be embodied in the 105 erection of foundries, train sheds and analogous structures, and in such instances steel, wood, or other materials may be utilized. The series of ventilating windows or cowls in the roof may also be multiplied 110 in accordance with the surface area covered by the roof and the particular purposes for which the structure is to be employed. It is further manifest that various alterations in the shape, form and proportions of the several structural features may be necessitated by the exigencies encountered in particular circumstances, and I consequently 115 reserve the privilege of resorting to all such obvious modifications as may be fairly embodied within the spirit and scope of the 120 invention as claimed.

Having thus fully described my invention, what I desire to claim and secure by Letters Patent is:—

1. In building construction, cantaliver 125 roof supporting girders tied together at their opposed ends, a roof ridge supported by said girders and having depending longitudinal ribs on its opposite edges, and a series of ventilating windows arranged upon 130

each side of and projecting above the roof ridge, and having upwardly inclined top walls leading to the ventilating openings, said ribs aiding in directing rising vapors 5 through the ventilating openings.

2. In building construction, transversely arranged cantaliver roof supporting girders tied together at their opposed ends, a roof ridge supported upon the connected ends of 10 the girders and having walls inclined downwardly from its apex, and a series of ventilating windows supported upon said girders on each side of the ridge and having top walls inclined upwardly in relatively opposite directions from the adjacent ridge wall 15 for the purpose of directing rising vapors through the window openings.

3. In building construction, cantaliver roof supporting girders disposed transversely of the roof, said girders being arranged in upwardly converging pairs tied together at their opposed ends, a roof ridge supported upon the connected ends of each 20 pair of girders, a central roof section disposed below the plane of the roof ridges and supported by the cantaliver girders, a series of ventilating windows between the opposite edges of the central roof section and the respective roof ridges, and longitudinally 25 extending ribs integrally uniting the top walls of the windows to the ridge walls.

4. In building construction, cantaliver roof supporting girders tied together at their opposed ends, a roof ridge supported 30 upon the connected ends of the girders, a series of windows of saw-tooth form supported upon the girders on each side of the ridge and having top walls inclined upwardly from the adjacent ridge walls and 35 vertical walls extending upwardly from the girders to the outer ends of said top walls and provided with ventilating openings, a swinging window sash mounted in each of the openings, and ribs extending 40 longitudinally between the spaced trans-

verse girders at the juncture of said top walls of the windows with the roof ridge, said ribs directing the rising vapors against 50 said top walls and through the window openings.

5. In building construction, outer vertical supporting columns and central supporting columns, transverse cantaliver girders extending from the outer vertical columns to the central columns, roof ridges supported 55 by said cantaliver girders on opposite sides of the roof center, a central roof section disposed below the plane of the roof ridges and supported by the cantaliver girders, vertical walls on the outer edges of said roof section 60 provided with ventilating openings, parallel longitudinal series of saw-tooth windows supported by the girders on opposite sides of each of the roof ridges and having top walls inclined upwardly from the ridges 65 and vertical walls at their outer ends, the vertical walls being provided with ventilating openings, said central roof section including oppositely extending upwardly inclined walls leading to the respective central 70 series of ventilating openings.

6. In building construction, upwardly converging cantaliver roof supporting girders, a roof ridge supported upon the upper ends 75 of said girders and having oppositely extending, downwardly inclined walls, and a series of ventilating windows supported by said girders on each side of the ridge and projecting above said ridge walls, said windows having inwardly and downwardly inclined top walls integrally joined to the respective longitudinal edges of said roof ridge.

In testimony whereof I hereunto affix my signature in the presence of two witnesses. 85

CHARLES F. DINGMAN.
